AUTOMOBILE WHEEL

Phillip Cravits, 545 S. Niagara St.,
Burbank, Calif. 91505

Continuation-in-part of design applications Ser. No.
241,867, 241,870 and 241,887, all Apr. 6, 1972, all
now abandoned. This application Apr. 4, 1973,
Ser. No. 347,907

Term of patent 14 years

Int. Cl. D12—08

U.S. Cl. D14—30 R

FIG. 21

FIG. 22

FIG. 1 is a perspective view of an automobile wheel showing my new design;

FIG. 2 is a top plan view of said automobile wheel;

FIG. 3 is a side elevational view of said wheel showing the outer side thereof;

FIG. 4 is a side elevational view showing the inner side of said wheel;

FIG. 5 is a vertical view taken along line 5-5 of FIG. 3;

FIG. 6 is a horizontal sectional view taken along line 6-6 of FIG. 3;

FIG. 7 is a side elevational view showing the outer side of a modified form of my design, and is identical to the design of FIGS. 1-6, except that five spokes are employed in place of four spokes;

FIG. 8 is a side elevational view showing the inner side of said wheel of FIG. 7;

FIG. 9 is a perspective view of another automobile wheel showing my new design;

FIG. 10 is a top plan view of said automobile wheel of FIG. 9;

FIG. 11 is a side elevational view of said wheel of FIG. 9 showing the outer side thereof;

FIG. 12 is a side elevational view showing the inner side of said wheel of FIG. 9;

FIG. 13 is a vertical view taken along line 13-13 of FIG. 11;

FIG. 14 is a horizontal sectional view taken along line 14-14 of FIG. 11;

FIG. 15 is a side elevational view showing the outer side of a modified form of the design of FIGS. 9-14, and is identical to the design of FIGS. 9-14, except that five spokes are employed in place of four spokes;

FIG. 16 is a side elevational view showing the inner side of said wheel of FIG. 15;

FIG. 17 is a perspective view of yet another automobile wheel showing my new design;

FIG. 18 is a top plan view of said automobile wheel of FIG. 17;

FIG. 19 is a side elevational view of said wheel of FIG. 17 showing the outer side thereof;

FIG. 20 is a side elevational view showing the inner side of said wheel of FIG. 17;

FIG. 21 is a vertical view taken along line 21-21 of FIG. 19;

FIG. 22 is a horizontal sectional view taken along line 22-22 of FIG. 19;

FIG. 23 is a side elevational view showing the outer side of a modified form of my design, and is identical to the design of FIGS. 17-22, except that five spokes are employed in place of four spokes; and

FIG. 24 is a side elevational view showing the inner side of said wheel of FIG. 22.

This is a continuation-in-part of design patent applications Ser. No. D. 241,867, D. 241,870, and D. 241,887 all filed Apr. 6, 1972 and all now abandoned.

I claim:

The ornamental design for an automobile wheel, substantially as shown and described.
